UNITED STATES PATENT OFFICE.

JOHN HAYS HAMMOND, JR., OF GLOUCESTER, MASSACHUSETTS.

SYSTEM OF RADIO TELEGRAPHY AND TELEPHONY.

1,372,425.

Specification of Letters Patent. Patented Mar. 22, 1921.

Application filed June 15, 1912, Serial No. 703,836. Renewed February 5, 1919. Serial No. 275,198.

To all whom it may concern:

Be it known that I, JOHN HAYS HAMMOND, Jr., a citizen of the United States, residing at Gloucester in the State of Massachusetts, have invented certain new and useful Improvements in Systems of Radio Telegraphy and Telephony, of which the following is a specification.

My invention relates to systems of radio 10 telegraphy and telephony, and relates more particularly to a system for the simultaneous operation of two or more high-powered wireless stations in the same neighborhood without interfering with each other, and the simultaneous transmission and reception of 15 a plurality of messages at each station.

The principal feature of the invention is a system of synchronously rotating interrupters which alternately connect transmitters and receivers to the antenna in such a manner that the receiver is inoperative when the transmitter is operative, and vice-versa. When the entire apparatus is at one station for use with one antenna, the interrupters 20 are mechanically connected so as to rotate synchronously. If two nearby stations are operated on this system, the motors for the interrupters are electrically connected, in any manner well known in the art, to obtain 25 synchronous rotation. In this case the two stations would transmit simultaneously and receive simultaneously, with respect to each other. That is, at each station the antenna would be connected to the transmitter and 30 the receivers would be disconnected at the same instant, so that neither station could receive during the instant that either transmitter would be connected for operation.

If the interrupters be revolved at a speed 40 which will produce an ultra-audible interrupting rate, each station can transmit and receive simultaneously without mutual interference. In addition to this freedom from mutual interference my system possesses a 45 very high degree of selectivity, since the receivers are tuned to a plurality of predetermined characteristics of the transmitted wave signals.

However, any speed of the interrupter or 50 commutator may be used that is suitable, and synchronism of the rotating interrupters or commutators may be attained by either wire or either wave connection between the different stations.

Referring to the drawings:—

Figure 1 represents a radio telegraph and telephone station on my system.

Fig. 2 represents a similar radio telegraph and telephone station in the vicinity of the station shown in Fig. 1.

In Fig. 1, H is a high-frequency alternator or other oscillatory current generator connected through coupling coils L² and L with antenna A. In circuit with antenna A are an interrupter I, coil L₁, and either a telephone transmitter T, or an interrupter I⁴ and a key K, according to the position of the switch S. This antenna circuit is grounded at E. The interrupter I has a frequency above the limits of audibility, and the interrupter I⁴ has a frequency within the limits of audibility. The above described apparatus constitutes the transmitting side of the station.

Also connected to antenna A is an open receiving circuit comprising an interrupter I², a coil L⁴, and a variable condenser C. This circuit is also grounded at E. The interrupters I and I² are both mechanically connected to the motor M, and are both operated at a rate above the limits of audibility, in such a manner that they are not in contact at the same time, but so that when one makes connection, the other is out of connection. Coupled to the receiving antenna circuit by means of the coils L² and L³ is the closed oscillatory circuit composed of inductance coil L⁶ and variable condenser C², which closed oscillatory circuit, by the action of rectifier R, supplies energy to receiving telephone P, and also, through coupling coils L⁸ and L¹⁰, to a circuit having a lower frequency, composed of inductance coil L¹⁰, condenser C⁴ and receiving telephone P². The telephone P is used to receive telephone messages, and the telephone P² is used to receive telegraph signals.

In Fig. 2 is shown a station similar to that in Fig. 1. H¹ is a high-frequency alternator, whose frequency is preferably different from that of alternator H. H¹ is inductively connected with transmitting antenna circuit A¹ I¹ L¹ S¹ E¹, which also includes either telephone transmitter T¹ or interrupter I⁵ and key K¹, according to the position of switch S¹. The antenna is also connected with the receiving circuit I³ L³ C¹, which is also grounded at E¹. This receiv-

ing circuit is inductively coupled to the closed oscillatory circuit $L^7 C^3$, which latter circuit, by means of the rectifier R^1 , supplies energy to the receiving telephone P^1 and to the comparatively low-frequency circuit containing coil L^{11} , condenser C^5 and receiving telephone P^3 .

Interrupter I^6 has a rate within the limits of audibility. Interrupters I^1 and I^3 have a rate above the limits of audibility, and are both mechanically connected to the motor M^1 . Motors M and M^1 are electrically connected, either by wire or otherwise, so as to operate synchronously, and in cases where both the stations shown in Figs. 1 and 2 are combined in one station, the motors M and M^1 may be connected mechanically.

Antenna circuits $A L^4 C E$ and $A^1 L^5 C^1 E^1$, and closed oscillatory circuits $L^6 C^2$ and $L^7 C^3$ are tuned to high frequencies, such as are suitable for electric wave transmission, and circuits $L^{10} C^4 P^2$ and $L^{11} C^6 P^3$ are tuned to frequencies within the limits of audibility, so as to receive telegraph signals from distant stations. These circuits of each station are in resonance with the electric wave characteristics of distant transmitting stations with which they are respectively in operative communication, and the characteristics of the transmitted electric waves from each station shown in Figs. 1, and 2 are in resonance with the receiving circuits of the respective distant stations with which they are in operative communication. The corresponding circuits of the stations in Figs. 1 and 2, however, should not be in tune with each other, as these stations are not intended for radio communication with each other, but are designed to be in communication with distant stations, without interfering with each other.

Various changes and modifications, within the skill of those versed in the art, may be made in the particular apparatus shown and described herein, without departing from the spirit of my invention, provided the means set forth in the following claims be employed.

I claim as my invention:

- 50 1. In a system of radio telegraphy and telephony, a plurality of stations, transmitting and receiving apparatus at each of said stations, said stations being operatively connected to transmit at the same time and to receive at the same time, and automatic means operatively connected with said transmitting and receiving apparatus to cause said stations to transmit simultaneously and to receive simultaneously.
- 60 2. In a system of radio telegraphy and telephony, means for transmitting and receiving at a plurality of stations, including interrupters alternately connecting the antennæ with the receiving and the sending apparatus, so that the receiving apparatus at

all the stations are connected synchronously and the sending apparatus at all the stations are connected synchronously, said interrupters being operated at a rate above the limits of audibility without breaking the operating continuity.

3. In a system of radio telegraphy and telephony, a plurality of sending and a plurality of receiving sets of apparatus, and means for interrupting all the sets of sending apparatus synchronously and all the sets of receiving apparatus synchronously and for interrupting the sending apparatus and the receiving apparatus alternately at a rate above the limits of audibility. 80

4. A method of radio telegraphy and telephony which consists in causing a plurality of stations to coöperate automatically in such a manner as to transmit simultaneously and to receive simultaneously, and in causing each of said stations to transmit and to receive alternately. 85

5. A method of radio telegraphy and telephony which consists in causing a plurality of stations to coöperate automatically in such a manner as to transmit synchronously and to receive synchronously, and in causing each of said stations to transmit and receive alternately at a rate above the limits of audibility. 90

6. In a system of radio telegraphy and telephony, a plurality of stations, each comprising transmitting apparatus and receiving apparatus; means for operatively connecting said stations synchronously, and means for causing all of said transmitting apparatus to operate alternately with all of said receiving apparatus. 95

7. In a system of radio telegraphy and telephony, a plurality of stations, means operatively connecting the stations for causing them to transmit simultaneously and to receive simultaneously, and means for causing said stations to transmit and receive alternately. 105

8. In a system of radio telegraphy and telephony, a plurality of stations, means for causing said stations to transmit and receive electric waves having a plurality of characteristics, and means operatively connecting said stations for causing said stations to transmit electric waves simultaneously and to receive electric waves simultaneously and to transmit and receive electric waves alternately. 115

9. In a system of telegraphy and telephony, the combination with a source of electrical oscillations, of means operative either to interrupt said oscillations at the will of an operator, or to impress irregular undulations corresponding to sound waves upon said oscillations, means for receiving either interrupted electrical oscillations or said electrical oscillations having irregular undulations corresponding to sound waves. 125 130

impressed thereon, and means operatively connecting said first mentioned means and said second mentioned means, and automatically operative to cause said first mentioned means to become operative alternately with said second mentioned means.

10. In a system of telegraphy and telephony, the combination with a source of electrical oscillations, of means operative either to interrupt said oscillations at the will of an operator, or to impress irregular undulations corresponding to sound waves upon said oscillations, means for receiving either interrupted electrical oscillations or 15 electrical oscillations having irregular un-

dulations corresponding to sound waves impressed thereon, and means operatively connecting said first mentioned means and said second mentioned means and automatically operative to cause said first mentioned means to become operative alternately with said second mentioned means, and at a rate of alteration above the limits of audibility.

This specification signed and witnessed this 22nd day of May, A. D., 1912.
